NEWSPAPER DISPENSING DEVICE

Daniel A. Perkins, 1433 W. 11th,
Santa Ana, Calif. 92703

Filed July 5, 1968, Ser. No. 12,641

Term of patent 14 years

Int. Cl. D20—01

U.S. Cl. D52—3

FIG. 1.

FIG. 2.

FIG. 3.

FIG. 4.

FIG. 1 is a perspective view of the front, top and side of the newspaper dispensing device design of this invention;

FIG. 2 is a side elevational view of the newspaper dispensing device of this invention;

FIG. 3 is a rear elevational view of the newspaper dispensing device of this invention; and

FIG. 4 is a bottom plan view of the newspaper dispensing device.

The undisclosed side of the dispensing device is a mirror image of the side shown.

The dominant features of the design reside in the full line portions shown in the drawings.

I claim:

The ornamental design for a newspaper dispensing device, substantially as shown and described.
